UNITED STATES PATENT OFFICE.

JUDSON BUCHANAN AND EDGAR M. HICKMAN, OF CHATTANOOGA, TENNESSEE, ASSIGNORS TO CHATTANOOGA PLOW COMPANY, A CORPORATION OF TENNESSEE.

WHEEL-PLOW.

SPECIFICATION forming part of Letters Patent No. 722,205, dated March 10, 1903.

Application filed August 11, 1902. Serial No. 119,310. (No model.)

To all whom it may concern:

Be it known that we, JUDSON BUCHANAN and EDGAR M. HICKMAN, citizens of the United States, residing at Chattanooga, in the county 5 of Hamilton and State of Tennessee, have invented a new and useful Improvement in Wheel-Plows, of which the following is a specification, reference being had to the accompanying drawings.

10 Our invention relates to wheel-plows. It is designed more especially for application to or embodiment in wheel-plows having on the furrow side two trailing caster-wheels, which travel in the furrows and bear against the 15 vertical wall of the furrow, as is well known in this art.

The object of our improvement is to form such a connection between said caster-wheels as will lead to the control of the movement 20 of the rear caster-wheel upon its vertical axis by the forward caster-wheel. Heretofore connections have been made between such caster-wheels permitting movement of the front 25 caster-wheel upon its vertical axis in either direction. In our improved construction the connection between said caster-wheels is such as to permit the turning of the front 30 caster-wheel upon its axis in only one direction.

An incidental feature of our improved construction is the absence of direct connection 35 between the team and the front caster-wheel. Neither the tongue nor the doubletree directly guide the front caster-wheel. Said wheel has a vertical axle journaled in the frame of the plow independently of the tongue and doubletree, so that said wheel is clearly a trailer; but its freedom to trail is by means 40 of the connection between the two caster-wheels limited to one direction. The connection between the two caster-wheels is such 45 that lateral movement of the rear caster-wheel in the forward direction is prevented when the front caster-wheel is in its normal position and such connection is so arranged as 50 that the force transmitted through said connection by the rear caster-wheel in its tendency to turn forward is received in line with the vertical axis of the front caster-wheel, so that said strain has no tendency to turn said front caster-wheel on its vertical axis.

In the accompanying drawings, Figure 1 is

a plan showing the vertical shafts of the two 55 caster-wheels located at the right-hand side of a wheel-plow and our improved connection extending from one of said shafts to the other. Fig. 2 shows the mechanism of Fig. 1 turned upon its right-hand side. Fig. 3 is a vertical section on the line 3 3 of Fig. 1. Fig. 4 is a vertical section on the line 4 4 of Fig. 1. Fig. 5 is a vertical section on the line 5 5 of Fig. 1. Fig. 6 is a detail view of the rear portion of 60 the connecting-rod 8. Fig. 7 is a plan of a frame of a wheel-plow with our invention applied thereto.

The general construction of such plows is 65 so well understood that we deem it unnecessary to illustrate a complete plow.

Referring to said drawings, A is the frame of a wheel-plow.

B is the land-wheel. C is the front 70 caster-wheel, and D is the rear 75 caster-wheel.

1 is the vertical axle of the front 80 caster-wheel, and 2 is the vertical axle of the rear 85 caster-wheel.

To the axle 2 is rigidly applied an arm 3, extending toward the right of the machine at right angles to the line of draft. To the axle 1 is applied a rigid arm 4, which is directed toward the free end of the arm 3. To the lower 90 face of the arm 4 is applied a plate or block 5. A bolt 6, extending vertically through the block 5 and the arm 4, adjacent to the free end of the latter, forms a vertical hinge or bearing for said block. Said hinge permits 95 movement in a horizontal plane; but such movement is limited by a suitable stop, so that the forward or free end of such block may move to the left away from said arm 4, but cannot move toward the right from beneath said arm 4. Such a stop is formed by a lug 7, extending upward from the left-hand side of said block, so as to bear against the left-hand side of the arm 4 when the free end of said block tends to move toward the right, 100 and a bolt 7^a may extend through said lug and bear against the arm 4. When said bolt is used, it constitutes a means of adjustment for establishing precisely the desired relation between the block 5 and the arm 4. Two lugs 105 or ears 5^a extend downward from the rear end of the block 5, parallel to said arm 4. The

front end of a bar or rod 8 extends between said ears, and a bolt 8^a extends horizontally through said ears and the end of said bar, whereby a hinge is formed between said block 5 and said rod.

On the arm 3 at the rear of the plow is pivoted a block 9 by means of a vertical bolt 9^a, extending through said block and said arm. Said block 9 has vertical parallel ears 10 9^b, between which lies the rear end of the bar 8. A bolt 9^c extends horizontally through said ears and the end of said bar, whereby a hinge is formed between said block and said bar. Thus we have the bar 8 joined to the 15 arm 3 by two hinges and to the arm 4 by two hinges—a vertical hinge and a horizontal hinge. The horizontal hinges are provided to permit vertical adjustment of one of the caster-wheel shafts with reference to the other.

20 The bar or rod 8 is preferably adapted to permit the free end of the arm 3 to swing rearward independently of the movement of the front caster-wheel. This can be accomplished by forming said bar or rod of two sections 8^b 25 and 8^c, the latter telescoping into the former. Under this arrangement the arm 3 may swing rearward and draw the section 8^c rearward in the section 8^b. At the front end of the section 8^c a stop 8^d, extending through the section 8^b, limits the forward movement of the section 8^c within the section 8^b.

It will be observed that the hinges formed by the bolt 9^a, the bolt 6, and the front vertical axle 1 are in line. Hence any forward 35 thrust imparted to the rod 8 by the arm 3 will be transmitted directly against said axle 1, and said thrust will have no tendency to turn said axle in either direction. Then so long as the front caster-wheel is in its normal position the strains imparted by the rear wheel to the arm 3 will not be transmitted to the front caster-wheel. Hence the front caster-wheel will turn on its vertical axis only in 40 response to resistance applied by the ground and in response to strains received through the lateral movement of the plow-frame by the team, and such movement of the front caster-wheel upon its vertical axis is limited to one direction—namely, the direction involving the movement of the free end of the arm 4 to the left, movement in the opposite direction being prevented by the stop 7 bearing against the left-hand side or edge of the arm 4.

55 We have ascertained by experiment that the front caster-wheel need not turn upon its vertical axis when the team turns toward the left, that it is feasible to then make the plow turn upon the land-wheel and the front caster-wheel, with said wheels in fixed relation to each other, as in an ordinary two-wheeled cart, the rear caster-wheel being then free to trail by reason of the slipping of the section 8^c rearward in the section 8^b of the connecting-bar 8. When the team turns to the right, the front caster-wheel is free to trail and throw the free end of the arm 4 to the left,

and this movement of said arm permits the forward movement of the connecting-rod 8, whereby the forward movement of the free 70 end of the arm 3 is permitted. This latter movement permits the rear caster-wheel to trail for the easy and short turning of the plow.

It will be understood that the hinges by 75 which the connecting-rod 8 is joined to the arms 3 and 4 may be varied without departing from our invention. The vertical hinge joining the rear end of the arm 4 to the connecting-rod 8 may be in any form suited to 80 permit action in one direction and prevent it in the other direction. For convenience we apply herein to said hinge the generic name "stop-hinge." In some cases it will probably be desirable to so form said stop-hinge as to 85 permit the axis of said hinge to move a little to the right of a line extending from the center of the vertical shaft 1 and the vertical hinge at the rear end of the rod 8 in order that slight accidental lateral movements of 90 the front caster-wheel may not "unlock" said stop-hinge. It will also be understood that the slipping or sliding bearing whereby the arm 3 is at all times free to swing rearward may be varied. For example, instead 95 of forming said rod 8 of telescoping sections the aperture through which the bolt 9^c extends may be elongated horizontally, as shown in Fig. 6, so that said bolt has a range of movement within said aperture. For convenience we apply to the connecting-rod 100 having provision for slipping, so as to at all times permit the arm 3 to swing rearward, the generic designation "slipping" connecting-rod.

105 We claim as our invention—

1. In a wheel-plow, the combination of the vertical front caster-wheel axle, 1, the vertical rear caster-wheel axle, 2, a rigid arm extending laterally from said axle, 2, at right angles to the line of draft, an arm, 4, extending rearward from said axle, 1, a connecting-rod hinged at its front end to said arm, 4, by means of a stop-hinge and hinged by its rear end to the free end of arm, 3, substantially as described.

2. In a wheel-plow, the combination of the vertical front caster-wheel axle, 1, the vertical rear caster-wheel axle, 2, a rigid arm extending laterally from said axle, 2, at right angles to the line of draft, an arm, 4, extending rearward from said axle, 1, a slipping connecting-rod hinged at its front end to said arm, 4, by means of a stop-hinge and hinged at its rear end to the free end of arm, 3, substantially as described.

3. In a wheel-plow, the combination of the vertical front caster-wheel axle, 1, the vertical rear caster-wheel axle, 2, a rigid arm extending laterally from said axle, 2, at right angles to the line of draft, an arm, 4, extending rearward from said axle, 1, a connecting-rod hinged at its front end to said arm, 4, by a horizontal hinge and by a vertical stop-

hinge and joined at its rear end to arm, 3, by a vertical hinge and a horizontal hinge, substantially as described.

4. In a wheel-plow, the combination of the vertical front caster-wheel axle, 1, the vertical rear caster-wheel axle, 2, a rigid arm extending laterally from said axle, 2, at right angles to the line of draft, an arm, 4, extending rearward from said axle, 1, a slipping connecting-rod hinged at its front end to said arm, 4, by a horizontal hinge and by a vertical stop-hinge and joined at its rear end to arm, 3, by a vertical hinge and a horizontal hinge, substantially as described.

5. In a wheel-plow, the combination of the vertical front caster-wheel axle, 1, the vertical rear caster-wheel axle, 2, a rigid arm extending laterally from said axle, 2, at right

angles to the line of draft, an arm, 4 extending rearward from said axle, 1, a block, 5, secured to said arm by a vertical hinge, a stop for limiting the movement of said block, a block secured by a vertical hinge to the free end of arm, 3, and a connecting-rod joined at its front end by a horizontal hinge to said block, 5, and joined at its rear end by a horizontal hinge to said block, 9, substantially as described.

In testimony whereof we have signed our names, in presence of two witnesses, this 31st day of July, 1902.
